WEAVING WITH EFFECT FROM ORIENTATION OF HIGH AND LOW PILE

Charles H. Masland, 2nd, Carlisle, Pa., assignor to C. H. Masland & Sons, Carlisle, Pa., a corporation of Pennsylvania

Application December 23, 1953, Serial No. 399,877

4 Claims. (Cl. 139—39)

The present invention relates to weaving of pile fabrics, particularly carpets and rugs, having a plurality of pile heights in the same transverse row, and also to the mechanism employed and the fabric produced.

The present application is a continuation in part of my copending application Serial No. 144,764, filed February 17, 1950, for Weaving With Effect From Orientation of High and Low Pile, now abandoned.

A purpose of the invention is to secure variation in pile height throughout a carpet or rug or any portion thereof according to a contour pattern or according to a random distribution, the contour variation in pile height occurring in the same transverse row of pile projections, and the contour pattern or variation in pile height running through the color pattern, if any, independently of the color pattern, and extending through areas of a single color in the color pattern.

A further purpose is to weave a pile fabric such as a carpet or rug over a set of wavy pile wires having the high and low points on the respective wires arranged according to a contour pattern or according to a random distribution.

A further purpose is to interpose two or more straight wires of different heights between wavy wires in weaving a pile fabric raised over the successive wires.

A further purpose is to interpose a plurality of straight wires of different heights in between each pair of wavy wires, providing pile yarn from which the wavy wires can pull pile when they are withdrawn and permissibly also providing uniform pile projections.

Further purposes appear in the specification and in the claims.

In the drawings I have chosen to illustrate one only of the numerous embodiments in which my invention may appear, selecting the form shown from the standpoints of convenience in illustration, satisfactory operation and clear demonstration of the principles involved.

Figures 1 to 4, inclusive, are diagrammatic views showing the weaving of a fabric in accordance with the invention, Figures 3^a and 4^a being enlargements respectively of Figures 3 and 4 to illustrate the weave previously produced.

Figure 5 is a fragmentary sectional perspective showing the wire set which employs two straight wires between each pair of wavy wires in accordance with the invention, the straight wires being of different heights.

Figure 6 is a conventional warpwise weave diagram showing the weave accomplished with the wires of Figure 5.

Figure 7 is a perspective of a wire which may be employed as one of the wavy wires in the invention.

In the drawings like numerals refer to like parts.

Describing in illustration but not in limitation and referring to the drawings:

In the prior art pile fabrics such as carpets and rugs have been woven in which the pile in certain transverse rows varies in height because it was woven over wavy

2

wires, and permissibly a straight wire has been interposed between the wavy wires.

By the present invention, novel textured effects are obtained by interposing two or more straight wires of different heights between adjoining wavy wires, and permissibly making one or more of the straight wires dominant over the wavy wires.

If the same pile warp ends wholly or in part are raised over the straight wires as over the wavy wires, it will be evident that the pile projections raised over the straight wire immediately ahead of the wavy wire will be converted to wavy pile projections when the wavy wire is withdrawn from the fabric, whereas the pile projections raised over the wavy wire will become straight when the wavy wire is withdrawn. It is not possible in this case to obtain predominant uniform ridges in the fabric, however, as only a single straight row of pile projections exists between wavy transverse rows. In accordance with the present invention, by placing two straight wires in adjoining relation, and using such wires of different heights, it will be evident that even if the row formed over one of the wires is converted to a wavy row by the withdrawal of a subsequent wavy wire, the other adjoining straight row or rows formed over straight wires is not thus affected, imparting a relatively strong and uniform feature to the pattern. Furthermore, since the adjoining straight wires are of different heights, a masking effect is obtained by which the pile can in some cases overhang the low wavy loops, and likewise the straight loops formed when the wavy wire is withdrawn can be dominated or masked by loops formed over a still higher straight wire as desired.

It will further be evident that where different pile warp ends are raised over the different wires, either because several warps are used in tapestry weaving or because a jacquard is employed in brussels weaving, even more variety can be obtained, since one or more colors of pile formed over straight wires which are relatively low can be partially masked by colors of pile formed over relatively high straight wires between wavy pile.

As far as the wavy wires are concerned, it will be understood that the relative high points on successive wires will be displaced laterally according to a contour effect or according to random distribution as desired.

The present invention is concerned with the use of noncutting wires, both for the wavy wires and for the straight wires, to produce uncut pile loops.

For many purposes it will be sufficient to employ two straight wires of different heights between each pair of wavy wires, but the number of straight wires in between any pair of wavy wires may vary with the conditions, being suitably two, three, four, five, etc., as desired. In fact any number of straight wires of different heights may be used between the wavy wires which does not destroy the contour pattern effect created by the wavy wires.

The weave employed may be of any suitable character, Figures 1 to 4 illustrating a conventional wilton weave to which the invention has been applied.

In this weave, binder warps 70 and 71 are withdrawn from a binder warp beam 72 through a reversing and tensioning device 73. Binder warp 70 is manipulated by binder warp heddle 74 and binder warp 71 is manipulated by binder warp heddle 75. Stuffer warp 77 is taken from stuffer warp beam 76 over tensioning device 73' and is manipulated by stuffer warp heddle 78. It will be evident, of course, that any desired number of stuffer warps may be employed.

Pile warps 80 and 81 are respectively taken from creel frames 82 and 83 through tensioning devices, not shown and manipulated through lingoe heddle 84 and 85 by any suitable mechanism such as a jacquard to raise and lower

the pile warps of the appropriate color at the proper position laterally of the fabric. While only two pile warps are shown, it will be understood, of course, that any desired number will be employed in multicolor pattern weaving, and that the invention is not limited to any particular number of pile warps of different colors.

A reed is shown at 86.

Starting with the first step in the cycle as shown in Figure 1, binder warp heddle 75, stuffer warp heddle 78 and lingoe heddles 84 and 85 are all down, while binder warp heddle 74 is in the upper position. A shot of weft 87 is taken under binder warp 70 and over binder warp 71, over stuffer warp 77 and over pile warps 80 and 81. The beat of reed 86 completes the first step.

At the beginning of the second step as shown in Figure 2, the binder warp heddles 74 and 75 are reversed, stuffer warp heddle 78 is raised and lingoe heddle 84 is fully raised as the color pattern may require and lingoe heddle 85 is raised half way as the color pattern may require. Wire 88 is inserted under pile warp 80 and above both binder warps, the stuffer warp and pile warp 81. A shot of weft 90 is taken under both pile warps, under binder warp 71, under stuffer warp 77 and over binder warp 70 and the lay is beaten up.

At the beginning of the third step, the stuffer warp heddle 78 is brought down, while the binder warp heddles remain in the same position and lingoe heddles 84 and 85 are brought down. A shot of weft 91 is taken under binder warp 71 and over binder warp 70, stuffer warp 77 and pile warps 80 and 81. The lay is beaten up.

At the beginning of the fourth step, as shown in Figure 4, binder warp heddles 74 and 75 are reversed, stuffer warp heddle 78 is raised, lingoe heddle 84 is fully raised as the color pattern may require, and lingoe heddle 85 is raised half way as the color pattern may require. Wire 92 is inserted beneath pile warp 80 and above pile warp 81, stuffer warp 77 and both binder warps, and a shot of weft 93 is taken over binder warp 71 and beneath both pile warps, stuffer warp 77 and binder warp 70. The lay is beaten up.

It will be evident that in this single cycle two wires 88 and 92 are inserted, and as the cycles continue successive wires will be introduced until the full wire set has been inserted, after which the wires are withdrawn, as well known in the art. Since all of the wires employed are noncutting wires, nothing unusual will happen during withdrawal until a wavy wire is withdrawn, in which case it will pull down the loops of the next preceding row of pile projections in which the same pile warp ends are raised in the pile.

Figure 5 illustrates a sequence of wires which are repeated over and over again in the set of wires. Wire 88 is a straight wire and next to it is another straight wire 92 which is here shown higher than wire 88 and desirably somewhat higher than the highest point on the wavy wire 94 which adjoins. Following wavy wire 94 is straight wire 95 which may or may not be of the same height as straight wire 88. Then follows straight wire 96, which may or may not be of the same height as straight wire 92, but desirably will be of a different height from straight wire 95, as shown. The next in the sequence is wavy wire 97. Wavy wires 94 and 97 have their high and low points differently displaced laterally to create a contour pattern.

When wavy wire 94 is withdrawn as may be seen from Figure 6, it pulls down the adjoining loop to a lower height if that loop is formed from the same pile warp end.

Figure 7 illustrates a wire constructed in accordance with the invention, having a head 98 of any suitable character to be engaged by the wire mechanism, and having low steps 100 within the shed. Intermediate steps 101 and high steps 102 within the shed are provided at intervals along the length of this wavy wire, at the top surface, in accordance with the contour pattern or random arrangement. The edges are smooth as in conventional

practice. Each successive wire has the high point and preferably also the low and intermediate points located at different positions along the length of the wire, for example, at different distances from the end of the wire and also, if desired, closer together or farther apart, depending upon the contour pattern.

The low and intermediate portions of the wire are connected by slope 103 in the direction of withdrawal, while the intermediate and high portions are connected by slopes 104 in the direction of withdrawal. The angles of the slopes over which the loops are pulled when the wire is withdrawn are matters of importance, and should be gradual, preferably not exceeding 15° and most desirably not exceeding 10° with respect to the longitudinal axis of the wire.

In Figure 6 loops 105 are raised over wires before the pattern change and loops 106 after the pattern change by the jacquard or the like.

In view of my invention and disclosure variations and modifications to meet individual whim or particular need will doubtless become evident to others skilled in the art, to obtain all or part of the benefits of my invention without copying the process and fabric shown, and I, therefore, claim all such insofar as they fall within the reasonable spirit and scope of my claims.

Having thus described my invention what I claim as new and desire to secure by Letters Patent is:

1. The method of weaving a pile fabric, including binder warps, stuffer warps, pile warps and wefts, which comprises interweaving various warps and wefts into a fabric, raising pile warps over a first noncutting pile wire having a plurality of heights on its upper surface throughout the length which is in the fabric before withdrawal, next raising pile warps over a second noncutting pile wire which is straight on its upper surface throughout the length which is in the fabric before withdrawal, next raising pile warps over a third noncutting pile wire which is straight on its upper surface throughout the length which is in the fabric before withdrawal but is of a different height from the second pile wire, subsequently raising pile warps over a fourth noncutting pile wire having a plurality of different heights on its upper surface throughout the length which is in the fabric before withdrawal and having different heights at the same lateral position in the fabric from those on the second pile wire, at least some of the pile warps raised over the first pile wire also being raised over one of the second and third pile wires, and subsequently withdrawing the wires successively in the order named, whereby the withdrawal of the first pile wire converts the pile projection formed from one of the second and third pile wires into wavy pile projections while the pile projections formed over the other of the second and third pile wires are not influenced by the withdrawal of the first pile wire.

2. The method of claim 1, in which the height of one of the second and third pile wires exceeds the height of the low portions of the first pile wire, whereby masking of low loops can occur when the pile wires are withdrawn.

3. The method of weaving a pile fabric, including binder warps, stuffer warps, pile warps and wefts, which comprises interweaving the various warps and wefts into a fabric, raising pile warp ends over successive noncutting pile wires including in sequence a first noncutting pile wire which is wavy on the upper surface over which the pile warps are raised, a plurality of straight noncutting pile wires of different heights at least one of which is higher than the low portions of the first pile wire, and then a second noncutting pile wire which is wavy on its upper surface over which the pile warps are raised, but which has its high points at different lateral locations from those on the first pile wire, the high points of successive wavy pile wires being arranged according to a contour pattern effect, at least some of the pile warp ends raised over the fourth pile wire being raised over

one of the second and third pile wires, and withdrawing the successive pile wires from the fabric in the order named, whereby a contour pattern is created running through the fabric, certain pile warp ends forming pile projections over one of the second and third pile wires being converted to wavy pile projections and pile warp ends over the other of the second and third pile wires forming straight pile projections.

4. The method of weaving a pile fabric including binder warps, stuffer warps, pile warps and wefts, which comprises interweaving the various warps and wefts into a fabric, raising selected pile warps from a plurality of pile warps of different colors in accordance with a color pattern over successive noncutting pile wires including in sequence a first noncutting pile wire which is wavy on the upper surface over which the pile warps are raised, a plurality of straight noncutting pile wires of different heights and then a second noncutting pile wire which is wavy on its upper surface over which the pile warps are raised, but which has its high points at different lateral locations from those on the first pile wire, the high points of successive wavy pile wires being arranged according to a contour pattern effect, and certain of the pile warp

5

ends raised over the fourth pile wire also being raised over one of the second and third pile wires, and withdrawing the successive pile wires from the fabric in the order named and thus creating a contour pattern running through the color pattern of the fabric, the withdrawal of the fourth pile wire converting one of the rows of pile projections formed over the second and third pile wires into wavy pile projections and leaving the other of said rows of pile projections as straight pile projections.

10

15

20

ends raised over the fourth pile wire also being raised over one of the second and third pile wires, and withdrawing the successive pile wires from the fabric in the order named and thus creating a contour pattern running through the color pattern of the fabric, the withdrawal of the fourth pile wire converting one of the rows of pile projections formed over the second and third pile wires into wavy pile projections and leaving the other of said rows of pile projections as straight pile projections.
